BENDING MACHINE

Edward J. De Witt, Winnetka, Ill., assignor to
 Wallace Supplies Manufacturing Co., Chicago,
 Ill., a corporation of Illinois

Application July 13, 1950, Serial No. 173,605

2 Claims. (Cl. 153—54)

1

This invention relates to bending machines for shaping pipes, rods and similar materials and is particularly concerned with improvements in a machine for bending metal pipe or rod into curved or coil formation.

It is a general object of the invention to provide a machine for bending a length of relatively heavy metal pipe or similar material into a curved or coil formation of predetermined diameter.

It is a more specific object of the invention to provide a bending machine which comprises a pair of spaced bending rollers arranged on fixed axes and a cooperating movable bending roller which is mounted for adjustable setting and resetting relative to the fixed rollers whereby to facilitate the feed of the material being bent between the rollers and to permit repeated bends to be made to a predetermined diameter.

It is a further object of the invention to provide a machine for bending metal rod or pipe material into coil formation which comprises a pair of driven back-up rollers arranged on fixed axes and in relatively close but spaced relation in combination with a forming or bending roller or die which is mounted for adjustment relative to the back-up rollers to permit it to be set in spaced relation thereto for providing a coil of predetermined diameter with one pass of the material between the back-up rollers and the bending roller.

It is another object of the invention to provide a machine for coiling pipe or rod material wherein a pair of spaced back-up rollers are arranged for receiving a length of pipe between the same and a forming roller which is mounted for adjusted reciprocable movement laterally of the back-up rollers, the rollers being so arranged that the path of movement of the material between the rollers may be predetermined by adjustment of the forming roller whereby coils of substantially constant diameter may be formed repeatedly on the machine without changing the adjustment of the forming roller.

It is a still further object of the invention to provide a pipe coiling machine of the type described wherein the forming roller is mounted for predetermined adjustable movement relative to the back-up rollers and wherein the forming roller may be moved gradually from an initial position spaced from the back-up rollers to its final predetermined bending position during the beginning of the coiling operation without interrupting the movement of the material as it passes between the rollers.

It is another object of the invention to provide a coil bending machine wherein the back-up

rollers are fixed and the bending roller is mounted on one end of a pair of hydraulically operated links and the other end of the links is mounted on a pivot which is adjustably positioned relative to the back-up rolls whereby the final bending position of the bending roller may be predetermined by adjustment of the pivot and the bending roller may be initially moved out of its final bending position to permit the material being bent to be placed between the bending roller and the back-up rollers, the bending roller being thereafter movable into final bending position by extension of the links.

It is a still more specific object of the invention to provide a machine for bending metal pipe or rod material into coil formation which comprises a pair of spaced back-up rollers each having a fixed axis and means for rotating the same in combination with a bending roller which is mounted on a carriage arranged for movement in a path extending laterally of the back-up rollers, the carriage being connected to one end of a pair of extensible links, the other end of the links being connected to a pivot formation which is adjustable along the path of movement of the bending roller carriage and power means for extending and contracting the links whereby the bending roller may be adjusted for bending successive coils of substantially the same predetermined diameter and whereby the bending roller may be initially moved out of bending position for insertion of the material between the same and the back-up rollers and thereafter gradually moved into the predetermined bending position relative to the back-up rollers.

It is another object of the invention to provide a coil bending machine wherein the forming roller is mounted for reciprocating movement relative to the back-up rolls and adjustable means is provided for determining the limit of the approach of the forming roll relative to the back-up rolls which adjustable means includes an abutment formation which is adjustable and a ram-actuated wedge movable between the abutment formation and an abutment surface associated with the forming roller.

It is still another object of the invention to provide a bending machine for fabricating curved shapes from metal pipe or rod material which comprises a pair of driven back-up rollers arranged on fixed pivots and in spaced relation to each other in combination with a bending roller which is movable in a predetermined path laterally of the spaced back-up rollers and extending between the same, the bending roller being

mounted on a movable carriage and means being provided for moving the carriage to selectively position the bending roller in an initial non-bending relation and in predetermined final bending relation relative to the back-up rollers.

These and other objects of the invention will be apparent from a consideration of the bending mechanisms which are shown by way of illustration in the accompanying drawings, wherein:

Fig. 1 is a front elevation with portions broken away of a bending machine incorporating therein the principles of the invention;

Fig. 2 is a side elevation of the bending machine;

Fig. 3 is a vertical section taken generally on the line 3—3 of Fig. 1;

Fig. 4 is a transverse section taken generally on the line 4—4 of Fig. 3;

Fig. 5 is a detail view taken generally on the line 5—5 of Fig. 1;

Fig. 6 is a section taken generally on the line 6—6 of Fig. 1; and

Fig. 7 is a partial front elevation of a modification.

Referring now to the drawings, there is illustrated in Figs. 1 to 6 a machine which embodies the principal features of the invention and which is adapted to bend a length of elongate material into coil formation, the machine being particularly designed for the cold bending of relatively heavy material such as, for example, iron pipe of an inch or more in diameter. However the machine is adapted to bend materials of various size and cross section to provide curved shapes or coil formations of various kinds, depending upon the adjustment and operation of the same and the length and character of the material operated upon.

The illustrated machine comprises a relatively heavy and rugged supporting frame consisting of a base structure 10, front and rear wall forming plates 11 and 12, a top wall forming plate 13 and suitable connecting side wall forming members 14 and 15.

A pair of identical back-up rollers 16 are mounted in laterally spaced relation near the bottom and forwardly of the front frame plate 11. The rollers 16 are carried on the forward ends of a pair of shafts 17 which extend a substantial distance beyond the forward frame plate 11 and which are journaled at 18 and 19 in the front and back frame plates 11 and 12. The back-up rollers 16 are provided on their edges with grooves 20 to accommodate material of circular cross section such as a round metal pipe or rod indicated at 21. The shafts 17 are each provided with a gear 22 which is located adjacent the inside of the front frame plate 11 which is in driven relation with a gear 23 mounted on a drive shaft 24 which is also journaled between the front and rear frame plates 11 and 12 at 25 and 26 below and between the shafts 16. The drive shaft 24 is provided with a sprocket or pulley 27 which is connected by a chain or belt 28 with a sprocket or pulley 29 on the driven shaft 30 of a speed reducer 31 which is connected in driven relation with a suitable driving motor 32, the speed reducer 31 and motor 32 being mounted on the end frame plate 14 in any desired manner.

A bending roller 33 of approximately the same diameter as the rollers 16 and having a corresponding groove 34 in the peripheral edge is mounted on a shaft 35 which is journaled for free rotation in a movable carriage 36 which com-

prises a pair of front and rear plate members 37 each of which is movable in vertically extending slot 38 in the front and rear frame plates 11 and 12. Each of the carriage plates 37 is provided along the inside vertical edges thereof with guideway forming grooves or recesses 39 and cooperating cover plates 40. The vertical edges of the frame plates 11 and 12 which define the slots 38 are preferably reduced in section as illustrated at 41 to provide a machined surface for closer fitting and alignment in the grooves 39 of the carriage plates 37. A cross bar 42 connects the carriage plates 37 above the shaft 35 and carries a sleeve 43 which is connected to one end of the lowermost one of a pair of links 44 which are pivotally connected to each other by a pivot pin 45. The upper end of the uppermost link 44 is secured to a sleeve 46 which is journaled on a cross bar 47 extending between a pair of front and rear plate members 48 which form with a top cross plate 49 a movable pivot block or frame 50 for adjustably positioning the upper end of the links 44. The plates 48 are provided with guideway formations and are mounted along their vertical edges for vertical sliding movement in the slots 38 in the front and rear frame plates 11 and 12 in the same manner as carriage plates 37. The top cross plate 49 is rotatably connected intermediate its ends with the lower end of a vertically extending adjusting screw 51. The screw 51 extends in threaded relation through a boss 52 in the top frame plate 13. The position of the pivot frame 50 and the cross bar 47 carried thereby may be adjusted vertically in the slots 38 by rotation of the adjusting screw 51 which is provided with a square head 53 for receiving a wrench or other operating tool.

A hydraulic operating cylinder 54 is mounted between the front and rear frame plates 11 and 12 by means of laterally extending pins 55 which are seated in bearing members 56 which are attached in aligned relation on the inside faces of the frame plates 11 and 12. The piston member 57 is pivotally connected at its free end on the pivot 45 which connects the links 44.

The hydraulic cylinder 54 is connected by suitable hose connections (not shown) with a source of fluid pressure which may be housed in the base 10 of the machine, if desired, and which is controlled by an operating valve. By controlling the flow of the fluid in the cylinder 54 the piston rod 57 may be moved into or out of the cylinder to contract or extend the connected link members 44 and thereby to move the bending roll 33 toward and from the back-up rolls 16.

The pivot frame 50 provides an anchorage for the upper end of the links 44 which anchorage may be adjusted by operation of the screw 51. The hydraulic cylinder 54 is positioned so that when the piston 57 is fully extended the links 44 are in fully extended relation and the bending roller 33 is at the lowermost limit of its movement away from the pivot frame 50. By varying the adjustment of the pivot frame 50 the final bending position of roller 33 may be varied while by controlling the movement of the links 44 the bending roller 33 may be initially moved out of bending position to permit the material being bent to be threaded into the machine and then moved gradually to final bending position.

A pair of pitch rollers 58 are arranged at opposite sides of the back-up rollers 16 and at the proper angle to the same to guide the material as it is fed between the back-up rollers 16 and the bending roller 33. Each of the pitch rollers

58 is mounted so that it may be adjusted toward and from the forward plate 11 on which it is supported to vary the pitch or distance between the coils when the material is being bent into a coil formation. The rollers 58 are mounted on a shaft 59 which is journaled in a pair of supporting end plates 60 projecting forwardly from a supporting bar or plate 61 which is provided with a central mounting member 62 arranged to telescope within a mounting socket 63 extending forwardly of and secured to the front face of the frame plate 11. The supporting bar 61 is provided with a pair of rearwardly extending adjusting screws 64 which project through suitable apertures in a pair of plates 65 extending parallel with the frame plate 11 from the socket forming member 63. Adjusting and locking nuts 66 are provided on the screws 64 so that the pitch rollers 58 may be moved to the desired position and locked against further movement.

The pivot frame 50 may be supplied with a pointer 67 and the forward plate 11 with a co-operating scale, indicated at 68, which is properly calibrated to indicate the curvature to which the material will bend when the pivot frame is adjusted to different positions for a particular size of material.

In using the device the screw 51 is rotated to adjust the pivot frame 50 to provide for the proper bending position of the bending roller 33 when the links 44 are extended by the hydraulic cylinder 54. The piston 57 is then moved to retracted position to contract the links 44 and move the roller 33 out of the bending position and away from the back-up rollers 16. The end of the material to be bent may then be positioned between the back-up rollers 16 and the bending rollers 33 after which the hydraulic cylinder 54 may be actuated to move the bending roller 33 downwardly either before or after back-up rollers 16 have begun to rotate to feed the material through the machine. The fluid pressure in the cylinder 54 is in most cases controlled to gradually move the roller 33 to its final bending position after the back-up rolls 16 have begun to rotate. The movement of the bending roll 33 to its final bending position may be accomplished very quickly relative to the movement of the material through the machine so that only a very short length of the material at the beginning of the operation is not bent to the proper diameter. This material may be removed as waste upon completion of the bending operation. The gradual movement of the roller 33 into final bending position after the material is started between the rollers eliminates the difficulty heretofore encountered in starting the material through the machine with the bending roll initially in bending position, particularly where a relatively sharp bend or a coil of relatively small diameter is being formed with heavy metal material. When the material is being bent into coil formation the pitch rollers 58 are initially adjusted to provide the desired distance between adjacent coils of the material.

In Fig. 7 there is illustrated a modified form of mechanism for controlling the movement of the bending roll, the remainder of the machine which is not illustrated being identical with that already described. The bending roll 100 is mounted on a carriage 101 which is slideable in a guideway 102 formed by slots in the frame plates 103. A pivot or abutment frame or block 104 is arranged for movement in the guideway 102 above the carriage 101 and provided with an adjusting screw

105 connected to the top of the machine to adjust it to the desired position in the guideway 102. The abutment frame 104 is provided with a roller 106 which is mounted in supporting brackets 107 on the bottom of the frame 104 while the carriage 101 is provided with a corresponding roller 108 which is mounted in brackets 109 on the top of the same. A hydraulic cylinder 110 is pivotally mounted at 111 in the frame of the machine and the piston member 112 is provided on its end with a block 113 having the lower face 114 beveled on the outer end thereof, the top surface 115 of the block 113 being generally parallel to the longitudinal axis of cylinder 110. The block 113 forms a wedge which is adapted to move between the rollers 106 and 108 upon extension of the piston member 112. With this construction when the abutment frame 104 is adjusted to the desired position and the piston member 112 is retracted by controlling the fluid in the cylinder 110 the carriage 101 carrying the bending roller 100 is free to move upwardly in the guideway 102 until the rollers 106 and 108 engage, the bending roller 100 being moved away from the back-up rollers (not shown) with which it cooperates in the bending operation. After the material has been positioned between the bending roller 100 and the cooperating back-up rollers the hydraulic cylinder 110 is actuated to move the piston 112 forwardly and engage the surfaces 114 and 115 of wedge block 113 between the rollers 108 and 106 whereby to force the carriage 101 downwardly in the guideway 102 to carry the bending roller 100 toward the back-up rollers and move it into bending position relative thereto.

While specific details of construction have been referred to in describing the illustrated forms of the invention, it will be understood that other details of construction may be resorted to within the spirit of the invention.

I claim:

1. A bending machine comprising a supporting frame, a pair of back-up rollers rotatably mounted in spaced relation on said frame, said frame having a guideway formation extending laterally of said back-up rollers and aligned with the space between the same, a pair of support members mounted in said guideway, means for adjustably positioning one of said support members in said guideway in fixed relation to said back-up rollers, a bending roller rotatably mounted on the other of said support members, a pair of links pivotally connected at one end to each other and pivotally connected at the other end to said respective support members, and hydraulic means connected to said links for extending and contracting said links, said links and said hydraulic means being so constructed and arranged that operation of said hydraulic means moves said bending roller away from said pair of back-up rollers a sufficient distance to permit a work piece to be positioned between the same and the bending roller, and thereafter moves said bending roller toward said pair of back-up rollers to a position for bending the work piece to a predetermined curvature by rotation of said rollers, and drive means independent of said bending roller to rotate said pair of back-up rollers.

2. In a bending machine, a pair of spaced plate members forming a supporting frame, a pair of bending rollers arranged in fixed relation outboard of said frame, said pair of bending rollers being mounted on spaced axles journaled in said

plate members, a guideway in said plate members extending laterally of the space between said pair of fixed bending rollers, a pair of carriages mounted for movement in said guideways, means for adjustably securing the carriage remote from said bending rollers in fixed relation in said guideway, a third bending roller arranged outboard of said frame on an axle journaled on the other one of said carriages, collapsible links pivotally connected at one end to said pair of carriages, said links being connected at their other ends to each other and to a power means and said power means being under the control of the operator for collapsing and extending said links to move said carriages relative to each other in said guideway, said links and said power means being so constructed and arranged that operation of said power means moves said other one of said carriages away from said fixed bending rollers for positioning a work piece therebetween and thereafter moves said other one of said carriages towards said fixed bending rollers

5 for bending the work piece to a predetermined curvature and means independent of said third roller for driving said pair of fixed bending rollers whereby to permit successive work pieces to be bent to predetermined curvature by rotation of said rollers.

EDWARD J. DE WITT.
